CARPET RETAINER

William S. Long III, 735 Carlton Ave.,
Plainfield, N.J. 07060

Filed Aug. 3, 1972, Ser. No. 277,516

Term of patent 14 years

Int. Cl. D25—01

U.S. Cl. D13—7 R

FIG. 1

FIG. 2

FIG. 3

FIG. 4

FIG. 5

FIG. 6

FIG. 1 is a front elevational view of a carpet retainer, showing my new design.

FIG. 2 is a rear elevational view thereof.

FIG. 3 is a top plan view thereof.

FIG. 4 is a bottom view thereof.

FIG. 5 is a right end elevational view thereof, which is a mirror image of a left end elevational view.

FIG. 6 is a perspective view, showing a portion of the carpet retainer in its normal environment, with the bottom portion of the retainer anchored to a floor panel, and the top portion of the carpet retainer holding the edge of the carpet in place, said dotted line portions being for illustrative purposes only.

I claim:

The ornamental design for a carpet retainer, as shown and described.
